US00D872503S

(12) **United States Design Patent** (10) **Patent No.:** **US D872,503 S**
(45) **Date of Patent:** **** Jan. 14, 2020**

(54) **PILLOW**

(71) Applicant: **DG International Holdings Limited**,
London (GB)

(72) Inventor: **Simon Little**, Middlesex (GB)

(73) Assignee: **DG International Holdings Limited**,
London (GB)

(**) Term: **15 Years**

(21) Appl. No.: **29/662,492**

(22) Filed: **Sep. 6, 2018**

(51) **LOC (12) Cl.** **06-09**

(52) **U.S. Cl.**

USPC **D6/601**

(58) **Field of Classification Search**

USPC D6/601, 382, 383; D24/191

CPC A47G 2009/1018; A47G 9/10; A47G 9/1081; A47G 9/0253; A47G 9/1045; A47G 9/1072; A61G 7/072; A61G 13/121; A61G 7/07; A61G 13/1225; A47C 16/005; A47C 20/00; A47C 20/02; A47C 20/027; A47C 20/04; A47C 7/383

(57) **CLAIM**

The ornamental design for a pillow, as shown and described.

DESCRIPTION

FIG. 1 is a perspective view of a pillow showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The broken lines represent elements which form no part of the claimed design.

1 Claim, 7 Drawing Sheets
